UNITED STATES PATENT OFFICE.

HERMANN LEMP, OF LYNN, MASSACHUSETTS, ASSIGNOR TO GENERAL ELECTRIC COMPANY,
A CORPORATION OF NEW YORK.

DEVICE FOR SIMULTANEOUSLY CONTROLLING THE SPARK AND THROTTLE OF AN INTERNAL-COMBUSTION ENGINE.

No. 896,305.

Specification of Letters Patent.

Patented Aug. 18, 1908.

Application filed June 30, 1906. Serial No. 324,195.

To all whom it may concern:

Be it known that I, HERMANN LEMP, a citizen of the United States, residing at Lynn, county of Essex, State of Massachusetts, have invented certain new and useful Improvements in Devices for Simultaneously Controlling the Spark and Throttle of an Internal-Combustion Engine, of which the following is a specification.

10 This invention relates to internal combustion engines in which provision is made for advancing the spark at the same time that the throttle is opened, and vice versa. If the rate of spark advance is the same as the 15 rate of throttle opening, the result is satisfactory for full load and for no load, but not for intermediate loads. From no-load to half-load the spark is not advanced enough to properly ignite the charge: the ignition being 20 too late and the charge too great. This causes a loss in efficiency, a considerable portion of the heat being wasted in the exhaust.

The present invention, which overcomes this difficulty, consists in a combination of a 25 spark-control comprising a lever, and a throttle mechanism including a lever, with a single operating lever, whereby the spark lever is given a motion proportionate to the sine and the throttle lever to the versed 30 sine of the angle through which the operating lever is moved to and fro. The result is that while the controlling lever is moved at a uniform speed, yet during the first half of its movement the spark advances rapidly, but 35 the throttle opens slowly: the rate of speed of the spark lever decreasing toward the end of the movement and that of the throttle increasing. This construction and arrangement relieves the operator of all mental effort in regulating the spark with reference to 40 the throttle: the proper adjustment being obtained automatically.

In the accompanying drawing, Figure 1 is 45 an elevation of an internal combustion engine equipped with my improved controlling devices; Fig. 2 illustrates the operation of the spark control; Fig. 3 shows the movements of the throttle; and Fig. 4 is a diagram of the motions of both spark lever and throttle lever.

The engine 1 has a throttle 2 and a spark-control shaft 3. The throttle is opened and closed by a lever 4, and the spark-control shaft carries a lever 5 by which it can be

turned to advance or retard the spark. A connecting rod 6 joins the throttle lever to an arm 7 on the rock-shaft 8. A second arm 9 on said shaft is connected by a rod 10 with the spark lever 5. The shaft 8 is also provided with an operating lever 11.

In the drawing the throttle is represented as closed and the spark retarded. On moving the lever 11 to the left, the arm 9 in passing to the midway dotted line position *a* causes the spark-control lever 5 to move to the dotted line position *a'*; while the arm 7, moving to the position *b* and describing the same angular movement as the arm 9, causes the throttle lever 4 to move only to the dotted line position *b'*. It will be noted that during this first half of the movement of the lever 11 the angular movement of the lever 5 is much greater than that of the lever 4. But during the latter half of the total stroke of the operating lever, the lever 5 travels only from *a'* to *a*, while the lever 4 moves from *b'* to *b*—a much greater distance. This result is due to the fact that the rock-arms 7 and 9 stand substantially at right angles to each other, and the arm 9 is nearly perpendicular to the rod 10 at the beginning of the stroke, while the arm 7 is nearly in line with its rod 6. The consequence is that the angular movement imparted to the lever 5 varies with the sine of the angle through which the arm 9 moves, while the angular movement imparted to the lever 4 varies as the versed sine of the angle through which the arm 7 moves,—the two angles being of course the same. The curves of these two movements are shown in Fig. 4: curve *x* being that of the spark-control and curve *y* that of the throttle. The diagram shows clearly how the spark lever moves at first rapidly and then more slowly, while the throttle moves at first slowly and then more rapidly.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new, and desire to secure by Letters Patent of the United States, is,—

1. The combination with the spark-con-

trol and the throttling mechanism of an internal combustion engine, of means for simultaneously regulating the advance and retardation of the spark with reference to the 5 opening and closing of the throttle which changes the point of ignition at a rate proportionate to the sine of a given angle while varying the opening of the throttle at a rate proportionate to the versed sine of said angle.

10 2. The combination with the spark-control lever and the throttle lever of an internal combustion engine, of means for moving the former at a rate proportionate to the sine of a given angle, and simultaneously moving the 15 latter at a rate proportionate to the versed sine of said angle.

3. The combination with the spark-control lever and the throttle lever of an internal combustion engine, of a single operating lever, and devices connecting said lever with the spark and throttle levers, whereby the 20

former of the two will move at a rate proportionate to the sine of the angle through which the operating lever moves, and the latter at a rate proportionate to the versed sine of said 25 angle.

4. The combination with the spark-control lever and the throttle lever of an internal combustion engine, of a rock-shaft carrying two arms at right angles with each other, and rods connecting said arms respectively with the said levers, the arm connected with the spark-lever standing substantially perpendicular to its rod, and the other arm lying nearly in line with its rod, when the throttle 30 35 is closed.

In witness whereof, I have hereunto set my hand this 28th day of June, 1906.

HERMANN LEMP.
